United States Patent Office

Des. 188,214
Patented June 14, 1960

188,214

COMBINED LAMP HOLDER AND LENS THEREFOR

Leonard Atkin, Springfield, N.J., assignor to Stone Manufacturing Co., a corporation of New Jersey

Filed Dec. 12, 1958, Ser. No. 53,742

Term of patent 14 years

(Cl. D48—20)

FIG.1

I claim:

The ornamental design for a combined lamp holder and lens therefor, substantially as shown.
